PANEL AND DIAL ASSEMBLIES

Edwin A. Neugass, Port Chester, N. Y.

Application April 13, 1953, Serial No. 348,343

11 Claims. (Cl. 116—124)

The present invention relates generally to panel and dial assemblies, and is particularly related to dials and the like for connection to control devices, such as, valves or switches, and which are mounted on a panel to schematically show the condition of a system having the control devices embodied therein.

It is common practice in aircraft and the like to provide control panels having schematic layouts of the fuel or electrical systems thereon. In such panels, the control knobs connected to the valves or switches of the fuel and electrical systems, respectively, are positioned at the locations on the schematic layouts corresponding to the junctures of the actual systems, and the position of each knob is intended to show graphically the conditions or flow paths actually existing at the corresponding juncture of the system. However, the existing knobs provided for the purpose described above project forwardly from the associated panel so that the markings on the knob for showing continuity of the flow system or circuit are not in the same plane as the portions of the schematic layout on the face of the panel and parallax results. Further, it has been difficult to obtain satisfactory illumination of the continuity markings from within the interior of the conventional knobs, with the result that the portions of the schematic layout on the panel are more intensely illuminated than the continuity markings carried by the knobs.

Accordingly, it is an object of the present invention to provide a dial, particularly for use on a panel having a schematic layout of the described character, wherein the dial and panel are co-planar to avoid any parallax.

Another object is to provide a dial of the described character having members extending therefrom for manual actuation and wherein such members are positioned and arranged to minimize the interference thereof with viewing of the continuity markings on the dial or the adjacent portions of the schematic layout on the associated panel.

Another object is to provide a dial of the described character for association with an internally illuminated panel, and wherein the dial is constructed to be illuminated internally with an intensity substantially the same as that of the panel.

Still another object is to provide a dial of the described character with an arrangement for connection to the related control device, such as, a valve or switch, so that manual rotation of the dial causes corresponding rotation of the related control device, and wherein the connecting arrangement separates conveniently to permit removal of the related dial with the panel supporting the latter.

In accordance with the present invention, the above, and other objects and advantages appearing in the following detailed description of illustrative embodiments, are achieved by providing circular recesses in the front face of a panel having a transparent core, a translucent layer superimposed on at least the front surface of the core and an opaque outer layer superimposed on the translucent layer, with such circular recesses extending into the transparent core and having concentric circular openings of smaller diameter extending through the panel. Such a

2

panel may be constructed in accordance with United States Letters Patent No. 2,518,726, to Charles N. Shlenker, issued August 15, 1950. Each dial is formed of transparent material and has a layer of translucent material superimposed on the front surface thereof with a layer of opaque material covering the translucent layer. The dial is of circular configuration to fit into the related recess of the panel so that the front faces of the panel and dials are flush. Each dial has a relatively small diameter portion fitting 5 rotatably in the related opening of the panel, and a relatively large diameter plate is connected to the back face of the dial behind the panel to prevent removal of the related dial from the panel. The large diameter plate is connected to the related dial by pins extending axially through the dial from the front and tapped into the plate. These pins are spaced from the axis of the dial and may be grasped for manually rotating the dial. Further, one of the pins extends rearwardly through the related plate and is received in a radial slot of a coupling secured to 10 the control device, such as, a valve or switch, associated with the dial. A suitable light source introduces light into the transparent core or body of the panel, and the opaque outer layer of the panel has portions thereof cut away to define the desired schematic layout of the associated system so that the parts of the translucent layer exposed at the 15 cutaway portions of the opaque layer are transilluminated to provide glareless illumination of the layout. The light from the core of the panel enters the dial through the confronting surfaces thereof, and the opaque layer of the dial is also cut away, in the form of the continuity portions of the schematic layout carried by the dial, so that the exposed portions of the translucent layer of the dial are also transilluminated to provide glareless illumination of the 20 portions of the schematic layout carried by the dial.

In order that the present invention may be fully understood, illustrative embodiments thereof are herein-after described in detail and shown on the accompanying drawings, forming a part hereof, and wherein:

Fig. 1 is a front elevational view of a panel having a schematic layout of a fuel system thereon and provided with dials embodying the present invention and showing the flow paths through associated valves;

Fig. 2 is a sectional view, on an enlarged scale, taken along the line 2—2 of Fig. 1;

Fig. 3 is a front elevational view of a panel having a dial associated therewith and constructed in accordance with another embodiment of the present invention and

Fig. 4 is a sectional view, on an enlarged scale, taken along the line 4—4 of Fig. 3.

Referring to the drawings in detail, and initially to Figs. 1 and 2 thereof, a panel 10 is there illustrated. The panel 10 is preferably formed from stock which is constructed in the manner disclosed in United States Letters Patent No. 2,518,726, to Charles N. Shlenker, issued August 15, 1950, and accordingly includes a core or body 11 of transparent preferably plastic material, for example, methyl methacrylate, a layer 12 superposed on at least the front face of the core 11 and formed of a translucent, preferably plastic material, for example, the class of polyvinyl or vinyl resins or materials, their polymers or co-polymers, such as, polyvinyl chloride, and an outer layer 13 superposed on the translucent layer 12 and formed of an opaque, preferably plastic material, for example, the class of polyvinyl or vinyl resins or materials, their polymers or copolymers, such as, polyvinyl chloride. Translucent and opaque layers, similar to the layers 12 and 13 described above may be provided on the rear face of the rear face of the transparent core 11. The several layers forming the stock of panel 10 may be bound or secured together in the manner set forth in the above identified patent, and the panel is cut to the desired dimensions and planform from such laminated stock. A suitable light

source (not shown) is associated with the panel 10 and operates to introduce light into the transparent body or core 11. The layers 12 and 13 at the front of the panel are preferably of contrasting tones or colors, for example, the translucent layer 12 is preferably white and the opaque outer layer 13 is preferably black and provided with a matte or low reflective finish to avoid glare or reflection of light from the front surface of the panel.

As seen in Fig. 2, the panel 10 is preferably mounted on a metal support plate 14 having brackets 15 secured to the back thereof to support various control devices 16, for example, valves, switches or potentiometers and the like. The support plate 14 has a circular opening 17 formed therethrough in registry with each of the control devices 16 mounted behind the support plate, and the panel 10 is also formed with a circular opening 18 positioned to be concentric with each of the plate openings 17 when the panel 10 is mounted on the plate 14. Each of the openings 18 extending through the panel 10 is formed with a relatively large diameter counter-bore or circular recess 19 at the front thereof.

The dial associated with each of the control devices 16 includes a circular plate or disc 20 which is formed from the same kind of stock as the panel 10 and hence includes a transparent core 21, a translucent layer 22 superimposed on at least the front face of the core 21, and an opaque outer layer 23 superimposed on the translucent layer 22, with the layers 22 and 23 preferably being white and black, respectively. The disc 20 has a stepped peripheral surface, as seen in Fig. 2, and includes a relatively large diameter front portion fitting rotatably in the related counter-bore or recess 19 of the panel 10 and a relatively small diameter rear portion fitting rotatably in the related opening 18. The stock from which the disc 20 is formed preferably has a thickness greater than the thickness of the panel 10 so that the rear surface of the disc is spaced rearwardly from the rear surface of the panel when the disc is rotatably seated in the related recess 19 and opening 18 of the panel.

The disc 20 is maintained in the related opening 18 and recess 19 of the panel by a metal disc 24 secured to the rear surface of the disc 20 and having a diameter larger than the diameter of the opening 18. A spring washer 25 is interposed between the metal disc 24 and the rear surface of the panel 10 and acts to continuously urge the disc 20 towards the rear, thereby ensuring that the large diameter portion of the disc 20 seats tightly on the bottom of the recess 19 to maintain the flush or co-planar relationship of the front faces of the panel 10 and the dial disc 20. In order to reduce the frictional resistance to rotation of the dial, the bottom of the recess 19 and the cylindrical wall of the opening 18 are undercut, as shown in Fig. 2, so that the disc 20 makes contact with the panel 10 only in the localized area indicated by the reference numeral 26.

In order to secure the metal disc 24 to the back of the plastic disc 20, the dial embodying the present invention includes two pins 27 and 28 formed of a hard and wear resistant metal, for example, steel, and having a dull black finish, such as a black oxidized finish, to provide a surface on the pins of low specular gloss. The pins 27 and 28 include relatively large diameter slotted head portions and reduced diameter stems extending therefrom to form radial shoulders between the heads and stems. The pins 27 and 28 extend axially from in front of the disc 20 through suitable openings 29 and 30, respectively, provided at diametrically opposed locations in the disc 20 and spaced from the center of the latter. The stems of the pins 27 and 28 are provided with threaded portions 31 and 32, respectively, which engage in suitable tapped holes formed in the metal plate or disc 24. Washers 33 preferably are provided between the radial shoulders of the pins 27 and 28 and the front surface of the disc 20.

As seen in Fig. 2, the dial embodying the present invention is separably coupled to the related control device

16 by an arrangement which includes a metal disc 34 carried by a hub 35 receiving the actuating shaft 36 of the related device 16 and secured to the actuating shaft by a set-screw 37. The disc 34 is formed with a radial slot 38 opening at the periphery of the disc 34, and the pin 27 is formed with an extension 39 which is preferably tapered at its end and is extended axially into the slot 38. Since the pin 27 is displaced radially from the center or axis of rotation of the disc 20 and the disc 20 and shaft 36 are substantially in axial alignment, it is apparent that rotation of the dial, by manual action on the pins 27 and 28, will cause a corresponding rotation of the actuating shaft of the related control device 16. Further, the radial play of the pin extension 39 in the slot 38 permits the axes of the control device and the corresponding dial to be somewhat out of alignment without affecting the ease with which the parts of the coupling may be interengaged or separated, and this tolerance makes possible the production of the panel and dials as a completed assembly 20 which is installed, as a unit, on the support plate 14 having the various control devices mounted therebehind.

Fig. 1 illustrated by way of example, the use of dial assemblies embodying the present invention on a panel having the schematic layout of a fuel system thereon, 25 with the dials being located at the junctures in the system where the associated valves are disposed. The lettering and the fuel flow paths appearing on the faces of the panel and the dial disc are defined by cutting away the outer opaque layer of plastic lamination, for 30 example, by an engraving operation, so that the exposed portions of the underlying translucent layer are in the form of the desired lettering and fuel flow paths. Since the outer opaque layer is black and the underlying translucent layer is white, a sharp contrast is provided between the exposed portions of the translucent layer and the surrounding portions of the opaque outer layer so 35 that the lettering and flow path markings are clearly visible when viewed under ambient light. When light is admitted to the core 11 of the panel lamination, the core transmits the light to the translucent layer 12 and the exposed portions of the latter are transilluminated to provide glareless illumination of the markings on the panel 10. Further, at the edge of each opening 18 receiving a dial assembly, the light passes from the transparent core of the panel 10 into the transparent core of the disc 20 so that the exposed portions of the translucent layer on the disc 20 are also transilluminated to provide glareless illumination of the flow path or other markings on the dial disc 20. If the stock from which 40 the panel 10 and disc 20 are formed has a translucent layer and an opaque layer only on the front surface of the transparent core, the support plate 14 and the metal disc 24 of each dial assembly are preferably finished with a polished front surface to reflect the light tending to 45 escape from the rear surface of the core back into the latter.

Further, as seen in Fig. 2, the opaque outer layer 13 of the panel preferably extends over the outer or front portion of the side wall of the recess 19, as at 40, so that 50 light cannot escape toward the viewer through the space between the panel and the dial disc. In the example illustrated in Fig. 1, the schematic layout indicates the left hand main, tip and auxiliary fuel tanks, and the right hand main, tip and auxiliary fuel tanks with the conduits or 55 fuel lines extending from these tanks to tank selector valve controlled by a dial assembly embodying this invention. The face of the disc 20 of the dial assembly has continuity markings thereon showing the flow paths through the associated valve, and these continuity markings cooperate with the adjacent markings on the face of the panel to graphically show to the viewer the actual flow paths of the fuel for the various valve positions. In the fuel system schematically represented on the panel of Fig. 1, 60 branched fuel lines lead from the tank selector valve to on-off valves controlling the admission of fuel to engine 65

No. 1 and engine No. 2. Each of these on-off valves has a dial assembly associated therewith which is generally of the same construction as that heretofore described. However, the dial assemblies 41 and 42 each have opaque shields 43 and 44 secured to the front face of the dial disc 20a thereof, for example, by the pins 27a and 28a and other fastening members 45, with the shields extending radially beyond the periphery of the disc 20a to selectively cover or obliterate indicia or markings on the adjacent portions of the panel face. For example, when the on-off valve is positioned to supply fuel to the related engine, the continuity marking on the disc 20a registers with fuel pipe markings on the panel, and the word "On" engraved in the panel is uncovered while the word "Off" is covered by the shield 43, as shown by the dial assembly 42. However, when the valve is positioned to interrupt the supply of fuel to the related engine, the corresponding dial assembly, for example, the dial assembly 41 of the drawing, assumes a position in which the continuity marking on the dial disc 20a is out of alignment with the representations of the fuel conduits or pipes on the panel and the shield 44 covers the word "On" while the shield 43 is displaced to uncover the word "Off." Thus, with dial assemblies of the kind represented by the numerals 41 and 42, the viewer obtains a graphic picture of the condition of the related valve and the exposed lettering or indicia provides a further indication of the valve setting.

Although Fig. 1 shows a panel and dial assembly having a schematic representation of an aircraft fuel system, it is apparent that assemblies embodying the present invention may be employed on panels which schematically represent any other kinds of systems, for example, electrical or hydraulic systems and the like. Further, dial and panel assemblies embodying the present invention may be employed to good advantage in association with potentiometers or tuning condensers and the like to provide a parallax-free indication of the setting of the related device.

Referring to Figs. 3 and 4, a dial and panel assembly adapted for association with a potentiometer, tuning condenser and the like is there illustrated. This assembly includes a panel 10b, generally similar to the panel 10 described above, and a dial disc 20b which is generally similar to the previously described disc 20. It will be seen that the panel has a marking 46 engraved thereon adjacent the periphery of the disc 20b and the latter has a scale or calibration 47 engraved thereon to cooperate with the marking 46 and thereby indicate the setting of the associated device. Since the front faces of the disc 20b and panel 10b are co-planar, parallax is avoided and the dial may be accurately read even when viewed from a location displaced from the axis of the dial.

Further, in order to focus the viewer's attention on the indicating portion of the scale 47 engraved on the disc 20b, the entire surface of the recess and opening in panel 10b receiving the disc 20b is covered with an opaque coating 48 (Fig. 4), with the exception of a restricted area indicated by the broken line 49 on Fig. 3 which is bare, so that, only within the area defined by the line 49 adjacent to the marking 46 on the panel, light will escape from the core of the panel into the adjacent portion of the core of the disc 20b. Thus, only the markings of the scale 47 adjacent the marking 46 of the panel will be transilluminated, and the viewer will not be distracted by illumination of the other portions of the scale.

Figs. 3 and 4 also illustrate a modified construction which may be used in place of the pins 27 and 28 of the embodiment in Figs. 1 and 2. The pins 27b and 28b of Figs. 3 and 4 include a steel body 50 having a slotted head and a stem tapped into the metal disc 24b in back of the disc 20b. The stem of the steel body 50 in pin 27b has an extension 39b forming a part of the coupling arrangement (not shown) for connecting the dial to the associated device and which may be the same as the coupling arrangement of Fig. 2. A sleeve 51, preferably formed of

aluminum, is provided with a bore through which the pin 50 extends, and the bore of sleeve 51 is counter-bored at one end to receive the head of pin 50. When the pin 50 is threaded into the disc 24b, the sleeve 51 bears against the front surface of the disc 20b so that the latter is gripped between the sleeve and the disc 24b. The surface of the aluminum sleeve 51 is anodized black to provide a permanent finish of low specular gloss.

Since the pins 27 and 28 or 27b and 28b are relatively slender and spaced apart, they provide minimal interference to viewing of the markings on the dial and on the adjacent portions of the panel, while affording means by which the dial may be firmly grasped for rotation with the assorted valve, switch or other device.

Although illustrative embodiments of the invention have been shown and described in detail, it is to be understood that the present invention is not limited to these precise embodiments and that various changes and modifications may be effected without departing from the spirit of scope of the invention as defined in the appended claims.

What is claimed is:

1. A panel and dial assembly comprising a panel having at least one circular opening therein, a circular dial fitting in said opening and rotatable in the latter, said dial and panel having cooperating markings thereon, means preventing axial removal of said dial from said opening with the front faces of said dial and panel being co-planar so that the cooperating markings on the dial and panel may be viewed without parallax, and two slender, elongated members extending axially from said dial at diametrically opposed locations spaced from the axis of rotation of the dial to be grasped in effecting rotation of the dial while providing minimal interference to viewing of the cooperating markings on the dial and panel.

2. A panel and dial assembly comprising a panel having at least one circular opening therein, a device to be actuated mounted behind said panel and having a rotatable shaft in substantial axial alignment with the center of said opening, a circular dial fitting rotatably in said opening and having a flat front face, means holding said dial axially in said opening with the front face of said dial co-planar with the front face of said panel, slender, elongated members extending axially in the forward direction from said dial at locations spaced radially from the center of rotation of said dial and adapted to be grasped in rotatably manipulating the dial, axially separable coupling means between said dial and shaft including an extension on one of said elongated members projecting rearwardly from said dial, and a disc fixed on said shaft of the device to be actuated and having a radial slot formed therein to axially receive said extension.

3. A panel and dial assembly comprising a panel having at least one circular opening therein, a circular dial rotatably fitting in said opening and having a flat front surface, said dial and panel having cooperating markings thereon, means holding said dial axially in said opening with the front surface of the dial co-planar with the front surface of said panel so that the cooperating markings on said panel and dial may be viewed without parallax, said panel having other markings thereon at spaced locations adjacent the edge of said opening, and shield members secured to the front surface of said dial and extending radially beyond the periphery of the latter to selectively obliterate said other markings in different rotated positions of said dial.

4. A panel and dial assembly according to claim 3; further comprising slender, elongated members extending axially from the front surface of said dial at locations spaced radially from the center of the latter to be grasped in effecting rotation of the dial while providing minimal interference to viewing of the cooperating markings on the dial and panel.

5. A panel and dial assembly comprising a panel having at least one circular opening therein formed with an

enlarged diameter concentric recess at the front thereof, a circular dial fitting rotatably in said opening, said dial having a flat front surface, said dial and panel having cooperating markings on the front surfaces thereof, said dial further having a radial flange bounded by said front surface and fitting rotatably in said enlarged diameter recess to locate said flat front surface of the dial in the same plane as the front surface of the panel so that the cooperative markings on the front surfaces of said panel and dial may be viewed without parallax, a circular plate disposed in back of said dial and having a diameter greater than the diameter of said opening, and means securing said circular plate to said dial with the peripheral portion of said plate overlying the back surface of said panel so that said flange on the dial and said circular plate cooperate to prevent removal of said dial from said opening, said means securing said circular plate to said dial including slender, elongated members extending axially through said dial at locations spaced radially from the center of the latter, said elongated members projecting forwardly from said dial to be grasped in effecting rotation of the latter and being threadably engaged in said circular plate to hold the latter against the back surface of said dial.

6. An assembly according to claim 5; further comprising a device to be actuated by said dial and having a rotatable actuating shaft, means supporting said device in back of said panel with said shaft substantially in alignment with the center of said dial, a coupling member on said shaft and having a radially extending slot therein, and an extension on one of said slender, elongated members projecting axially in back of said circular plate and engaging in said radial slot to communicate the rotation of said dial to said actuating shaft of the device.

7. A panel and dial assembly comprising a panel having at least one circular opening therein, a circular dial rotatably fitting in said opening and having a flat front surface, means holding said dial in said opening with the front surface of the dial in planar alignment with the front surface of said panel, said panel and dial each including a core of transparent material having a layer of translucent material superposed on at least the front face of the core and a layer of opaque material superposed on said translucent layer, said panel and dial having openings formed through the opaque layers at the front thereof and exposing portions of the underlying translucent layer which define cooperative markings at the front surfaces of said panel and dial for viewing without parallax, said panel and dial having at least portions of their confronting edges at said circular opening exposed to each other so that light admitted to said core of the panel is transmitted by the latter to transilluminate said exposed portions of the translucent layer of the panel and through said exposed confronting edge por-

5 tions into said transparent core of the dial to transilluminate at least those exposed portions of the translucent layer of the dial disposed adjacent the exposed confronting edge portions of the panel and dial, and slender, elongated members extending axially from said dial and projecting in front of the latter at locations spaced radially from the axis of rotation of the dial to be grasped for effecting rotation of the latter.

8. An assembly according to claim 7; including an opaque layer covering a substantial portion of the edge of said panel confronting the edge of said dial at the opening so that the exposed portions of the translucent layer of said dial are transilluminated only when said dial is in rotated positions in which said exposed portions 10 of the translucent layer are remote from the covered portion of the edge of said panel.

9. An assembly according to claim 7; including opaque shield members mounted on the front surface of said dial and extending radially beyond the periphery of the latter selectively obliterate certain of said openings formed 15 in the opaque layer at the front of said panel.

10. An assembly according to claim 7; wherein said panel has an enlarged diameter circular recess at the front and concentric with said opening, and said dial has a radial flange bounded by the front surface of the dial and fitting rotatably in said recess, and said means holding the dial in the opening includes a circular plate disposed in back of said panel and having a diameter greater than the diameter of said opening; and wherein 20 said elongated members extend through said dial and threadably engage in said circular plate to hold the latter to the back surface of said dial concentric with the latter so that said flange and plate cooperate to prevent removal of said dial from the related opening.

11. An assembly according to claim 10; further comprising a device to be actuated by said dial and including a rotatable actuating shaft, means supporting said device in back of said panel with said shaft substantially in axial alignment with the center of said dial, a coupling member fixed on said shaft and having a radial slot, and an axial extension on one of said elongated members projecting behind said circular plate and engaging in said radial slot to communicate the rotation of said dial to the actuating shaft of the associated device.
